UNITED STATES PATENT OFFICE.

DAVID WILLIAM LANDES, OF PORTLAND, OREGON.

TESTING DEVICE FOR DRY BATTERIES.

Application filed June 16, 1921. Serial No. 477,962.

To all whom it may concern:

Be it known that I, DAVID WILLIAM LANDES, a citizen of the United States, and a resident of Portland, in the county of Multnomah and State of Oregon, have invented certain new and useful Improvements in Testing Devices for Dry Batteries, of which the following is a specification.

10 This invention relates to a testing device for dry batteries.

The object of the invention is to provide a device of the above character by which dry batteries of the type employed in connection with flashlights may be tested to determine whether or not the battery is sufficiently charged.

It is also an object of the invention that dry batteries of different capacities may be 20 tested.

It is a further object of the invention that the device be portable and inexpensive to manufacture.

Other objects and objects relating to details of construction, combination and arrangement of parts will hereinafter appear in the detailed description to follow.

The invention is illustrated by way of example in the accompanying drawings, in 30 which:

Figure 1 is a perspective of the device.

Figures 2 and 3 are transverse sections taken substantially on the lines 2-2 and 3-3, respectively, of Figure 1.

35 Figure 4 is a perspective view of the connector plate for the test lights.

Figure 5 is a perspective view of the slideable element of the testing device.

Figure 6 is a top plan view of the lower 40 strip or section and also the movable element associated therewith.

Figure 7 is a bottom plan view of the top strip or section with a portion broken away to more clearly illustrate the invention.

45 Referring to the drawings more particularly, a frame or base is provided comprising the top strip A and the bottom strip B, which are of wood and preferably of the shape shown. Each strip is provided 50 with a central longitudinal slot 10, said slots registering with each other, when the two strips are fitted together, as shown, in Figure 1. Each side wall of the slots is formed within an offset 11, said offsets forming a 55 pair of guideways adapted to slidably accommodate the tongues 13 of the block 14.

The bottom surface of the strip B is preferably covered with card-board sheeting 12. The bottom surface of the strip A is offset at its one end and in said offset there is fitted a plate 15; also in the same end of the strip A there is provided a plurality of openings, each being adapted to accommodate an electric lamp socket 16, Figure 3, said sockets being of the screw type as shown and adapted for receiving the plug portion of an electric lamp 17. The lamps 17 are of the type employed for flashlights and of different voltage. The sockets 16 are four in number, in the present instance, two being arranged adjacent each side of the strip A and each of said sockets extending into an opening 18 formed in the plate 15, so that they may be electrically connected with the plate 15.

A contact point 19 is extended from the inner end of the plate 15, said point having a suitable electrical connection with the plate 15, and from the point 19 there extends a tang 20 which is also connected with the contact post 21, said post being positioned as shown and formed with an inwardly extending end portion 22.

Upon one side of the slot 10 of the strip B, there is secured a pair of electric current conductor strips 23 and 24 and upon the other side a pair of similar strips 25 and 26. The conductor strips are equal in number to the lamps 17 and the forward end of each strip is adapted to be engaged by the contact terminal 27 of the associated lamp 17. The lamp with which the strip 23 connects is of greater voltage than the lamp with which the strip 24 connects, and likewise the lamp with which the strip 25 connects is of greater voltage than the lamp with which the strip 26 connects. The plate 15 and strips 23 to 26 are insulated from each other by cardboard sheeting or the like as shown.

Across the forward end of the block 14 there is suitably secured a strip 28 which is of spring metal and has a portion 29 extending along each tongue 13 of the block, said portion being formed in the shape of a bow 105 as shown which is adapted to frictionally engage the inner walls of the guideways in which the tongues 13 of the block slide. It will also be observed that the conductor strips 23 to 26 inclusive, each have their end disposed along the slot 10, slightly cut away as at 30 so that the shoes 29 of the block 14

may contact therewith. With the strip 28 there is connected the one end of an L-shaped clip 31, the other end of said clip being connected with the post 32, said post being carried by the block 14, as shown, and formed at its upper end with a forwardly projecting portion 33, said projection 33 being in alignment with the projection 22 formed on the post 21.

10 As well known dry batteries employed for flashlights are of different sizes and the greater the size the greater voltage lamp required therefor. Also the batteries increase proportionally in length with their size or capacity. In the present instance, it is intended that the lamp 17 which is associated with the strip 25 is of sufficient voltage to test a dry battery of a relatively high capacity, while the lights associated with the 15 remaining strips 23, 24 and 26 are adapted for testing dry batteries of lower capacity. When it is desired to test a battery, the operation is as follows:

20 The battery is laid in the slot 10 of the member A with its positive terminal connecting with the contact point 19, the block 14 is then moved forwardly until projection 33 of the post 32 engages with the negative electrode or the zinc shell which forms the 25 body of the battery. The length of the battery will determine with which of the conductor strips 23 to 26 inclusive, the post 32 will be electrically connected. If the battery 30 is of high capacity the length thereof will be sufficient so that the post 32 will be electrically connected with the conductor strip 25. If the battery is sufficiently charged the current will flow through the contact 19, 35 plate 15 and illuminate the light 17 which is associated with the strip 25 and thus test the battery. In case the battery tested is of 40 smaller capacity it will likewise be shorter in length and a different voltage lamp 17 will be illuminated.

45 Should it not be desired to drop the battery into the slot 10 of the member A, the same may be held so that one electrode will contact with the projection 22 of the post 21, while its other electrode will contact with the projection 33 of the post 32. The block 50 14 will of course be moved to effect this connection and thus bring the contact post 32 into electrical connection with the proper light 17.

55 While I have shown and described the preferred form, combination and arrangement of my invention, I wish it to be understood that I am aware of the fact that minor changes may be made by those skilled in the art without departing from the spirit thereof as indicated by the appended claims.

I claim:

1. A testing device of the character described, comprising a base, a block movable thereon, a contact carried by the base and in

alignment with said block, a plurality of electric lamps, each having its one terminal connected to said contact, a plurality of conductors, one for each lamp, and connected to the remaining terminal thereof, and each 70 conductor having its one end arranged in close relation to said block, a pair of bow springs carried by said block and adapted to engage said conductors, a contact carried by the block, and an electrical connection between said contact and bow springs. 75

2. A testing device of the character described, comprising in combination, a base consisting in a pair of strips made of insulating material, each strip being provided with an elongated longitudinally extending slot, said slots being adapted to register with one strip placed one upon the other, means for securing the said strips together, a block slideable within the slot formed by said strips, a contact point at one end of said slot, a plurality of electric lamps carried by the base, each having one terminal connected to said contact, a conductor strip extending from the remaining terminal of each light and having its one end disposed in close relation to a side of said slot, a contact point carried by the block, and means carried by said block electrically connected with said contact adapted to be brought to 95 engage either of said conductor strips. 90

3. A testing device of the character described comprising in combination, a base having a slot extending longitudinally thereof, a plurality of electric lamps carried by said base, a contact point or member in one end of said slot and connected to a terminal of each of said electric lamps, a block slideable in said slot, a conductor strip carried upon the block and having resilient side portions adapted to frictionally engage the side walls of the slot, a contact point or member carried by the block and electrically connected to the conductor strip, conductor wires extending from each remaining terminal of the lamps and each strip having its free end disposed adjacent the slot and adapted to be engaged by the side portions of said conductor strip carried by the block, for the purpose described. 100 105 110 115

4. A testing device of the character described, comprising in combination, a base having a slot extending longitudinally thereof, a plurality of electric lamps supported by said base, a contact post at one end of said slot and electrically connected to a terminal of each of said electric lamps, a block slideable in said slot, a spring bow positioned upon each side of said block and adapted to engage the side walls of said slot, a contact post carried by the block and electrically connected to each of said spring bows, a conductor element extending from the remaining terminal of each electric lamp and having its free end disposed for engage- 120 125 130

ment with one of said bow springs of the said conductor elements when said conductor elements are engaged by said movable member for the purpose described. 20

- 5 5. A testing device of the character described, comprising a base, a member movable longitudinally of the base, a contact point at one end of the base, a plurality of electric lamps each having one terminal connected to said contact point, a conductor extending from the remaining terminal of each lamp and the other ends thereof arranged in spaced relation and longitudinally of the base and adapted to be engaged 10 by said movable member, a contact point carried by the movable member, and adapted to be electrically connected with each of

6. A test unit including a base, a channel guideway, a contact member upstanding between the side walls of said guideway and at one end thereof, a contact upon said base and exposed within said guideway, an indicating means connected with said member and said contact, and a contacting member 25 slidably supported within said guideway adapted to cooperate with said contact whereby a battery may be accommodated 30 between the members closing a circuit therethrough and through said indicator.

DAVID WILLIAM LANDES.
